DOOR LATCH MECHANISM

Bert A. Quinn, St. Paul, Minn.

Application September 10, 1941, Serial No. 410,272

5 Claims. (Cl. 292—167)

My present invention provides an improved door latch mechanism of the type that can be utilized also as a lock and which is especially adapted for application to in-swinging doors.

By doors of the in-swinging type I intend to indicate those that swing into a room or enclosure, the interior of which is to be protected when the latch is converted, for example, into a lock. The customary bathroom door is a good illustration of an in-swinging door. Such a door when unlatched or free is opened from the outside by pushing or pressing inward thereon, and is opened from the inside by pulling inward on the door.

In my improved latch or lock mechanism I provide a latch mechanism with operating handles projecting both from the outer and inner sides of the door and, as a highly important feature, I provide latch mechanism which will be released from the outer side of the door by pushing or pressing inward on the outer handle and which will be released by pulling inward on the inside handle. With this arrangement pushing or inward pressure on the outside handle performs two functions, to wit: first, it releases the latch, and second, by the continued force in the same direction on the handle, pushes the door inward to open position; and an inward pull on the inside handle performs two functions, to wit: first, it releases the latch, and second, by a continued pull in the same direction, swings the door to open position.

In this improved device the latch bolt is preferably of the spring-pressed beveled type which automatically engages a latch plate or the like on the door frame when the door is moved to closed position; and in combination therewith and the features above indicated, I provide a lock device that is operative from the inner side of the door and which, when pressed or actuated, locks the latch bolt in its operative position and thereby converts the so-called latch bolt into a positively acting lock bolt.

The invention also involves certain other important novel features, all of which will appear in the following description of the drawings, wherein like characters indicate like parts throughout the several views.

Referring to the drawings:

Fig. 1 is a fragmentary view in elevation showing portions of a door and door frame with the improved latch mechanism applied thereto, some parts being broken away and some parts being sectioned, and some parts being sectioned on the line 1—1 of Fig. 2;

Fig. 2 is a horizontal section taken approximately on the line 2—2 of Fig. 1;

Fig. 3 is a horizontal section taken approximately on the line 3—3 of Fig. 1;

Fig. 4 is a vertical section taken on the line 4—4 of Fig. 2;

Fig. 5 is a vertical section taken on the line 5—5 of Fig. 3;

Fig. 6 is a vertical section taken on the line 6—6 of Fig. 2;

Fig. 7 is a view in perspective showing the latch bolt casing; and

Fig. 8 is a view in perspective showing the latch bolt retractor slide.

In this illustration of the invention, the numeral 10 indicates the inwardly swinging door and the numeral 11 indicates a door frame or casing provided, as shown, with a metallic latch plate 12 rigidly secured in a mortice thereof and having a perforation 13 for engagement with the latch bolt hereinafter described. The door jamb or frame adjacent to the latch plate 12 and in line with the perforation 13 is shown as provided with a recess 14 in which the latch bolt freely projects when the door is swung against the stop 15 of the door frame. The door, which is assumed to be an ordinary hinged door, is arranged to be opened by swinging movement in the direction of the arrow marked thereon in Figs. 2 and 3 and the said door when thus swung is assumed to be swung into the bathroom or other room or compartment. The operation of the door will be most conveniently illustrated by assuming that the latch mechanism is applied to the inwardly swinging door of a bathroom, but it will be understood that it may be applied to other doors.

For the application of the latch mechanism the door is bored through to form a quite large transverse opening 16 and from the free edge of the door is cut out to form an opening 17 that receives the latch bolt casing and leads into the transverse opening 16.

Extended into and through the recess 16 is a flattened tubular metallic latch casing 18 which preferably is formed integral with an anchoring plate 19 that is rigidly clamped to the outer face of the door by means of screws 20 applied as hereinafter described. In the drawings the plate 19 acts as an anchor for the casing 18 and, as shown, is covered by a thin metal casing 21 having, as shown, a plurality of inturned ears 22 turned under the edges of anchor plate 19, as best shown in Fig. 4, and is thereby held to said anchor plate. On the inner face of the door covering the

opening 16 is a flanged face plate or escutcheon 23, preferably of thin sheet metal. The anchoring screws 20, just above noted, work through the plate 23 with their heads preferably countersunk therein and with their threaded ends engaging with anchoring lugs 24 that project from the exterior of the casing 18. These screws 20, as now apparent when tightened, securely anchor the casing 18 with plate 19 pressed against the outer face of the door; and it is also apparent these screws 20 can be manipulated only from the inner side of the door.

The latch bolt casing illustrated is of special design and includes a plate-like anchoring head 25, a flat hollow portion 26, and two hollow legs 27 and 28. The said elements 27 and 28 are shown as formed from folded sheet metal plates, the flanges of which are bent into loose engagement. The inner end of the leg 27 is preferably closed at 29 to afford a base of reaction for the latch bolt actuating spring presently to be described. When the latch bolt casing shown in detail in Fig. 7 is applied in operative position, it will be rigidly secured to the door preferably by screws 30 passed therethrough and through a supplemental or reinforcing plate 31, see particularly Fig. 5.

The latch bolt already referred to may take various forms, but to adapt the same for the casing shown in detail in Fig. 7, said latch bolt 32 is bifurcated or formed with legs, one of which works in the leg 27 and the other in the leg 28. A coiled spring 33 is placed in the leg 27 and reacts against the bottom of said leg and against the longer and major leg of the latch bolt and tends to press the beveled end of said latch bolt outward for engagement with the recess in the latch plate 12.

As best shown, in Figs. 3, 4 and 5, the numeral 34 indicates a latch bolt retracting link formed with a longitudinal slot 35 and at its inner end with notches formed between lugs 36 and 37. The slotted end of retracting link 34 is attached to the minor leg of latch bolt 32 by a pin or rivet 38 that works through slot 35 and thus permits limited sliding movements of the latch bolt in respect to said link, all as will hereinafter more fully appear.

Fig. 8 shows in detail a latch bolt retracting slide involving a flat plate portion 39, having spaced prongs 40 projecting therefrom at right angles thereto. This plate 39 is arranged to slide in a guide formed by the anchoring plate 19 and co-operating face plate 21. As best shown in Fig. 4, the anchoring plate 19 is formed with laterally bulged horizontally extended portions 19a that define the upper and lower portions of the guide for the slide 39. By reference to Figs. 4 and 5 it will be noted that the prongs 40 engage notches formed in the inner end of the retracting link 34, between the lugs 36 and 37.

The latch actuating handles for this latch mechanism are preferably stamped from sheet metal but may be otherwise formed. The outside handle is indicated by the numeral 41 and the inside handle by the numeral 42. The inside handle 42 extends freely through a slot 43 in the inside facing plate 23 and the outside handle 41 extends freely through a slot 44 of the outside face plate 21. The inner ends of the said handles 41 and 42 are extended into the casing 18 and are overlapped and mounted on a common pivot pin 45 that is anchored in the casing 18.

The outside handle 41 is extended with a rea-

sonable clearance through an opening 46 formed in the slide plate 39 and when said outside handle 41 is oscillated, it will cause the plate or slide 39 to move therewith performing important operations that will appear in the description of the operation. For a purpose which will hereinafter appear, slide 39 is formed with a small perforation 47.

For converting the latch bolt into a lock bolt, 10 as above indicated, I provide a lock dog 48 that may take various forms but which, as shown and preferably, is of a special design. This lock dog 48 is pivoted at 49 to lugs on the casing 18, see particularly Figs. 2, 4, 5 and 6. This lock dog 48 has four active projections, to wit: a beveled end 50, a laterally bent contact lug 51, a laterally projecting lock lug 52, and a spring contact free edge 53. The numeral 54 indicates a short coiled spring that is compressed between the edge 53 and a spring bearing or base of reaction 55.

The end 50 of said latch dog is arranged to be engaged by the beveled end of a plunger 56 that works through a bearing sleeve 57 on the inside face plate 23. The beveled or inclined lug 51 of lock dog 48 is in the path of movement of the inner lock actuating handle or lever 42; and the lock lug 52 of said dog is normally out of the path of movement of the outside handle or lever 41, but is adapted to be projected into the path of movement thereof when plunger 56 is pressed inward to cause oscillation of said lock dog. Here, at this time, attention is further called to the fact that when the lock dog is in the normal or inoperative position shown in Fig. 4, spring 54 will be at one side of a dead center, when by operation of plunger 56 lock dog is moved into a locking position to intercept or prevent movement of outside handle, said spring will be on the opposite side of the dead center. The arrangement shown permits the lock dog to move only to or slightly beyond the extreme positions indicated.

As best shown in Figs. 5 and 6, the handles 41 and 42, at their pivoted ends, have overlapping portions; that these overlapping portions are substantially channel-shaped; and that there is a slight clearance at 58 which permits a slight movement of the one handle in respect to the other. It may be here stated that this clearance is sufficient to permit the flanges of the handle 42 to engage the inclined or beveled lug or ear 51 before the handle 42 engages and picks up the handle 41. The two handles are normally yieldingly held in positions shown in Figs. 2 and 3 by a coiled compression spring 59 that is seated against a knob 60 on the casing 18 and presses a spring cap 61 against the back or channel of the handle 41.

Operation

Certain features of the operation of the device have already been indicated, but the complete operation may be summarized as follows:

Normally the handles 41 and 42 will, by the spring 59, be held as shown in Figs. 2 and 3 with freedom for very slight movement of inside handle 42 without moving handle 41. This movement of handle 42, as will later appear, is sufficient to release the lock dog 48 after the latter has been set, but this action will be described further later on.

Normally, also, the latch bolt 32 will be projected in locking position by spring 33 and at such

time the rivet or pin 38 will be at the outer limit of the slot 35 of retracting link 34.

In fact, the link 34 at all times, and even when the door is open, limits the projecting movement of the latch bolt 32 to a position such as shown in Fig. 3.

It will first be assumed that the lock dog 48 is in its normal or inoperative position, as best shown in Fig. 4, and at which time the inclined or beveled trip lug 51 of said dog is out of the path of movement of said handle, as shown by dotted lines in Fig. 5.

Under these conditions if handle 42 be pressed or pushed inward toward the door or the handle 41 pulled inward in a direction away from the door, both handles will be oscillated and handle 41 will cause slide 39 to move therewith and the prongs 40 of said slide acting on retracting link 34 will retract latch bolt 32 and pull the latter out of engagement with the latch plate 12, thereby unlatching the door and freeing the same for inward swinging movement. Of course, when the door is thus released, the inward swinging movement thereof will, as already indicated, be produced either by pushing on the outer handle 41 or pulling inward on the inside handle 42. In closing the door, the latch bolt 32 automatically engages the opening in the latch plate 12.

To set the lock dog 48 in operative position to thereby convert the latch bolt into a lock bolt and lock the door, it is only necessary to press on the plunger 56. When the plunger 56 is thus pressed inward, it moves the lock dog into inoperative position with its lock lug 52 in the path of movement of outside handle 41, see Fig. 3, and this, as is obvious, will lock the outside handle so that it can not be manipulated to release the latch and open the door. However, from the inner side of the door to retract the bolt 32, it is only necessary to pull inward on the inside handle 42. Here attention must again be called to the fact that when the lock dog 48 is set in operative position as just above described, spring 59 will then be set outward slightly beyond a dead center so that it will then tend to hold said lock dog in a set or operative position. When inside handle 42 is pulled inward as just above described, the initial movement thereof will cause the flanges of said handle to engage the inclined trip lug 51 of said lock dog and move said lock dog back to its inoperative position, shown in Fig. 4, and in which position the spring 59 will then be set outward slightly beyond its dead center so that it will then tend to hold the lock dog in its inoperative position until the lock dog has again been set. To reiterate, this slight initial movement of inside handle 42, which takes place before it picks up outside handle 41, is sufficient to cause retraction of the lock dog, and hence, the movement of lock lug 52 out of the path of movement of handle 41 before handle 41 is picked up by handle 42.

From the foregoing it is obvious that it is important that the inside and outside handles be individual pivoted members, the one of which is capable of at least a slight movement in respect to the other to thereby cause the lock dog to be retracted or set back to inoperative position, for reasons already indicated.

It is anticipated that sometimes a child, for example, might lock itself in a bathroom by pressing on the plunger or lock actuating element 56. Hence, I have provided the small hole 47 in the slide 39 through which a nail or the like might be inserted and engaged with lock lug 52 of lock dog 48, as shown in Fig. 6, wherein by dotted lines

a nail or the like is rendered operative to release the lock dog and permit the door to be then opened by manipulation of either the inside or outside handle or lever.

It may be noted that the lugs 37 project to such an extent that when the retracting link 34 is forced through the leg 28, it will slightly expand the same and then when the said lugs pass out of the end of said leg contraction of the leg will prevent the said lugs 37 from being freely withdrawn through the leg, thereby holding the link against accidental withdrawal from the leg even before the latch bolt casing has been applied in the lock mechanism.

What I claim is:

1. In a door latch mechanism of the kind described, a casing insertable into a door, a double-ended two section handle structure extended through said casing and made up of reversely projecting sections pivotally connected to said casing for dependent and simultaneous pivotal movements, a yieldingly pressed latch bolt extended laterally from and mounted to slide in said casing, a latch bolt retracting means comprising a slide mounted on said casing and having means for operative engagement by said handle sections, and a retracting link operatively connected with said slide, said link having slide connection to said bolt permitting the latter to be normally projected and causing said bolt to be retracted when said slide is moved by said handle structure.

2. The structure defined in claim 1, in which said retracting slide is mounted at one side of said casing and directly connected to one of the handle sections for operation therewith, and said slide being indirectly connected to the other handle section through said first mentioned handle section.

3. In a door latch mechanism of the kind described, a casing insertable into a door, a double-ended two section handle structure extended through said casing and made up of reversely projecting sections pivotally connected to said casing for dependent and simultaneous pivotal movements, a yieldingly pressed latch bolt extended laterally from and mounted to slide in said casing, a latch bolt retracting means comprising a slide mounted on said casing having means for operative engagement by one of said handle sections and having a laterally projecting prong, a retracting link operatively connected with said prong, said link having slide connection to said bolt including a pin and slot permitting the latter to be normally projected and causing said bolt to be retracted when said slide is moved by said handle structure, whereby said latch bolt will normally be projected but will be retracted when said slide is moved by the cooperating handle member.

4. In a door latch mechanism of the kind described, a casing insertable into a door, a double-ended two section handle structure extended through said casing and made up of reversely projecting sections pivotally connected to said casing for dependent and simultaneous pivotal movements, a yieldingly pressed latch bolt extended laterally from and mounted to slide in said casing, a latch bolt retracting means comprising a slide mounted on said casing having means for operative engagement by one of said handle sections, and a retracting link operatively connected with said slide, said link having slide connection to said bolt permitting the latter to be normally projected and causing said bolt to

be retracted when said slide is moved by said handle structure, and a lock dog movably mounted in said casing to lock one of said handle sections against sufficient movement to retract said latch bolt, said lock dog being spring biased on its mounting from one side to the other of a dead center to hold said dog retracted or operative according to the position in which it is moved.

5. In a door latch mechanism of the kind described, a casing insertable into a door, a double-ended two section handle structure extended through said casing and made up of reversely projecting sections pivotally connected to said casing for dependent and simultaneously pivotal movements, a yieldingly pressed latch bolt extended laterally from and mounted to slide in said casing, a latch bolt retracting means com-

prising a slide mounted on said casing having means for operative engagement by one of said handle sections, and a retracting link operatively connected with said slide, said link having slide connection to said bolt permitting the latter to be normally projected and causing said bolt to be retracted when said slide is moved by said handle structure, a lock dog movably mounted on said casing and arranged to be manually set to lock one of the handle sections against sufficient movement to retract said lock dog, and the other handle section having a slight movement relative to said one handle section to operate said dog to restore the same to released position during said movement.

BERT A. QUINN.
